PITCHER

Carl O. Swanson, Minneapolis, Minn.

Application September 11, 1939, Serial No. 294,233

4 Claims. (Cl. 65—31)

This invention relates to improvements in pitchers or similar small vessels used for holding and pouring liquids.

The ordinary pitcher, as particularly exemplified by the cream pitcher used at the table, has one serious disadvantage. That is, the tendency of the last drop or two of the liquid or cream, after a quantity has been poured, to run down the side below the pitcher's spout and thus soil both pitcher and table and generally cause an unsightly and unsanitary condition. It is the primary object of my invention therefore to provide a pitcher having means for collecting the drippings from the spout or lip and returning them to the interior of the pitcher so that they cannot run down and drip from the sides.

A further object is to provide a pitcher and improved arrangement thereof in which the action of collecting and returning the drippings is entirely automatic and results from the normal tipping or canting of the pitcher in use.

Still another object is to provide a non-dripping attachment or mechanism for a pitcher in a simple and inexpensive form and of such construction and arrangement that it may be readily kept clean and free of unsightly matter.

These and other more detailed and specific objects will be disclosed in the course of the following specification, reference being had to the accompanying drawing, in which

Fig. 1 is a side view of a pitcher including my invention, the pitcher being shown at rest in normal position on the table and with a part broken away and in section to show my non-drip mechanism.

Fig. 2 is a front end view of the pitcher looking toward the spout or pouring lip thereof.

Fig. 3 is an enlarged, fragmentary vertical section along the line 3—3 in Fig. 2, the pitcher in this case being shown as canted for pouring out the contents.

Fig. 4 is a fragmentary plan view of the spout portion of the pitcher, the view being on the same scale as Figs. 1 and 2.

Fig. 5 is a view similar to Fig. 3, but showing a modified form of non-drip mechanism.

Referring now with more particularity to the drawing, the reference character A designates a pitcher of usual form having an open topped container or bowl B for containing the liquid, a base C for supporting the bowl, an outwardly extending and rounded pouring spout or lip D, and opposite thereto a handle E for lifting and tipping or canting the pitcher to pour out the liquid over the spout. This is but one of the usual forma-

tions of such vessels and it is to be understood that my invention may be applied as well to other containers having similar pouring spouts.

In the use of a pitcher of this kind there is a well known tendency for the liquid poured over the spout or lip to run down over the adjacent lower and frontal side of the spout, clinging to the surface of the pitcher until it finally falls to the table. In accordance with my invention a return passageway or opening 10 is formed 10 through the frontal wall of the pitcher a short distance below the spout D, but above the normal level of liquid in the pitcher, and on an angle declining or extending downwardly and inwardly into the pitcher away from the spout. The forward wall of the pitcher bowl is then molded and formed with a forwardly projecting shoulder or ledge 11 defining the lower forward margin of said opening 10 and this shoulder extends upwardly toward the lip D in the form of spaced side 15 portions 12.

The last drops or portions of the liquid poured over the lip D may as usual run down the under forward side thereof, but they will now be diverted or returned through the opening 10 to the 25 inside of the bowl B as the pitcher is returned to its normal resting position. The shoulder 11 and side portions 12 serve to confine this travel of the liquid and to direct it into the open forward end of the opening 10 as will be readily apparent. 30 The lower outer portion of the opening thus actually extends forwardly into the path of the liquid while the upper portion sets back to receive the liquid, due to the angle of the opening and formation of the shoulder 11. 35

In order to prevent the liquid from running directly out through the opening 10 as the pitcher is tilted forwardly, I provide a check or gate valve 13 which, in the embodiment of my invention shown in Figs. 1 through 4, is pivotally connected 40 at its upper side at 14 to a short sleeve or tube 15 inserted in the opening 10 and cemented or otherwise secured therein. This valve 13 is located at the inner end of said opening 10 and due to the aforesaid inclination of the opening the valve will 45 of its own weight normally hang in a position clearing the inner end of the opening (and of the sleeve 15 therein) at the lower side as indicated at 16. A weight or finger 17 on the valve may be provided to properly distribute the weight with 50 reference to the hinge or pivot 14 for this purpose.

In operation then the pitcher is manipulated in the usual manner and as it is tilted forwardly to pour the liquid the valve 13 will swing forwardly against the opening 10 and sleeve 15 55

therein (see Fig. 3) closing the same against the escape of the liquid, as will be clearly apparent.

As the pitcher is returned to level position the valve 13 will again swing open allowing the excess liquid to run back into the pitcher through the opening in the manner described.

5 To prevent the valve 13 from possibly sticking to the inner end of the valve 15, due to the action of the liquid, the said inner end may be beveled off as indicated at 18 to present a sharp edge for contact with the valve. The inner surface of the bowl B around and beneath the inner end of the opening 10 is recessed as shown at 19 in order to clear the valve 13 and allow the same 10 to be disposed forwardly and reduce its projection into the pitcher.

In Fig. 5 the use of the aforesaid sleeve 15 is dispensed with and in lieu thereof the valve 13 is hinged at 10 to a short mounting member 20 or stud 20 which is inserted in an inwardly opening recess or bore 21 formed in the pitcher above the opening 10 to properly support said valve adjacent the opening. The valve thus swings closed against the inner end of the opening 10 25 to seal the same and the margin of this opening is formed with an inwardly extending tapered rib 22 to prevent sticking of the valve. Other parts and the operation of this form of my invention are the same as above described.

30 It is understood that suitable modifications may be made in the structure as disclosed, provided such modifications come within the spirit and scope of the appended claims. Having now therefore fully illustrated and described my invention, what I claim to be new and desire to protect by Letters Patent is:

1. The combination with a pitcher including a pouring lip, of means for returning liquid from the outer surface of the lip to the pitcher, the 35 said pitcher having an opening through its side below the lip for this purpose, and a gravity operated valve operatively supported for closing said opening as the pitcher is tilted for pouring its contents and to clear said opening in the normal resting position of the pitcher, the said valve

being arranged at the inner end of the opening, and the pitcher having a recess in its inner surface around the said opening for receiving and partially enclosing the valve.

2. The combination with a pitcher having a 5 pouring lip, of means for returning liquid from the outer side of the lip to the interior of the pitcher, the said pitcher having an opening below the lip for this purpose, a sleeve in the opening, the inner end of the sleeve being obliquely 10 disposed, and a valve pivotally connected to the inner end of the sleeve and adapted to swing closed against said end when the pitcher is tilted for pouring and thereby prevent escape of liquid through the sleeve, the said valve being weighted 15 to swing clear of the inner end of the sleeve in the normal resting position of the pitcher.

3. The combination comprising a pitcher, a pouring lip thereon, the said pitcher having an opening in its wall below the lip and adapted to 20 return liquid running from the lip into the interior of the pitcher, the said pitcher having a recess in its inner surface above the opening, a stud member mounted in said recess and extended inwardly therefrom, a valve pivoted to 25 the inner end of said member and arranged to swing against the inner end of the opening and close the same as the pitcher is tilted for pouring, and the said valve being so supported with reference to the opening that it will swing away 30 from the opening in the normal resting position of the pitcher.

4. In a pitcher, a containing portion, a pouring lip extending upwardly and outwardly therefrom, the said containing portion having an 35 opening below the lip and said opening inclining upwardly and outwardly toward its outer end, a sleeve mounted in the opening, and a valve pivotally connected to an upper inner end portion of the sleeve for movement toward and away 40 from the inner end of the sleeve and adapted normally of its own weight to hang inwardly at its lower side clear from the said inner end of the sleeve.
